UNITED STATES PATENT OFFICE

EDMUND J. CLERGET, OF CHICAGO, ILLINOIS, ASSIGNOR TO AMERICAN ENGINEERING COMPANY, OF PHILADELPHIA, PENNSYLVANIA, A CORPORATION OF PENNSYLVANIA

STOKER

Application filed August 19, 1924. Serial No. 732,971.

My invention relates to stokers, having particular relation to hand operated stokers.

One object of my invention is to provide relatively simple means for positively feeding coal into and through a furnace without any packing of the coal due to one portion of the fuel bed pushing against a succeeding portion.

Another object of my invention is to provide a novel form of fuel supporting and feeding structure together with means for so modifying the supporting surface of said structure when the latter is moved bodily, that clinker formation is substantially avoided and the free passage of air through the fuel supporting structure facilitated.

A further object of my invention is to provide a stoker comprising means for feeding fuel into a furnace as the fuel bed is opened up and for, thereafter, so operating on the fuel bed as to close such voids as may have been formed by the preceding feeding movement, whereby the fuel bed may be maintained at a substantially uniform density.

A still further object of my invention is to provide a grate structure comprising a plurality of movable parts forming a grate surface and means for moving said grate structure into one position, wherein the grate surface is broken up into a plurality of step-like sections, and for moving said grate structure into another position, wherein the grate surface is substantially flat.

A still further object of my invention is to provide a grate of the class described, wherein a desired transverse section may be raised or lowered and moved forward or backward without materially affecting the structure of the fuel bed adjacent to said section.

Other objects and applications of my invention, as well as details of construction and operation, will be apparent from the following description and claims, wherein,

Fig. 1 is a vertical sectional view taken through a portion of a furnace equipped with my invention, the grate elements being shown in their flat or normal forward position;

Fig. 2 is a view similar to Fig. 1 but show-

ing the grate elements in their raised or rear position;

Figs. 3 and 4 are detail, vertical sectional views taken on the lines 3—3 and 4—4, respectively, of Fig. 1; and

Fig. 5 is a sectional view taken on the line 5—5 of Fig. 1.

In the illustrated form of embodiment of my invention shown in the drawings, I have omitted such details of the general structure as were not essential to the clear understanding of my present invention. The structure therein disclosed comprises front and rear walls 1 and 2 and side walls 4. A fuel supporting and feeding grate-structure 5 for the furnace extends from a point adjacent to the rear wall 2 through a furnace opening 6 in the front wall 1 to a point just beyond the same and it is movably mounted on inclined pairs of rails 7 and 8 carried by the side walls 4, respectively, all as will appear more fully hereinafter. One method of supporting the rails 7 and 8 on the side walls 4 is shown in Figs. 3 and 4, wherein the side wall 4 is provided with an inclined groove 9 forming a supporting shoulder 10 of sufficient depth to receive the rail 8 only. Rail 7, which is to be supported outside of the groove 9, is mounted on a horizontal plate 11 which extends into the groove 9 intermediate the rail 8 and the shoulder 10.

The rails 7 and 8 support rollers 12 and 13, which are mounted on pivot rods 14 and 15, respectively. The pivot rods 14 and 15 support a number of intersecting transverse and longitudinal series of plates which constitute the grate surface. As shown in Fig. 5 of the drawing, each longitudinal series of plates extends from a movable hopper plate 16 (Fig. 1) positioned at the outer end of the grate construction to an anchor plate 17 positioned at the inner end of the grate construction, and it comprises successive pairs 18 of relatively wide and narrow plates 19 and 20, respectively, or so-called grate and hinge plates. Each transverse series of plates, however, extends between the furnace side walls 4, 4 and it comprises a plurality of pairs of grate and hinge plates 18.

The outer ends of the grate plates 19 are mounted on the longer pivot rods 15, while the inner ends thereof are mounted on the shorter pivot rods 14. The outer ends of the succeeding hinge plates 20 are mounted on the shorter pivot rods 14 and the inner ends thereof are mounted on the longer pivot rods 15. The hopper plate 16 extends from the outer end of the grate plate 19 nearest the furnace opening 6 and it is movably supported by the pivot rods 15 and the rollers 13. The anchor plate 17 has the inner end thereof rigidly secured to a supporting member 22, which is spaced from the rear wall 2, and the outer end thereof is mounted on the pivot rod 15.

As previously pointed out, the rails 7, which support the rollers 12 carrying the pivot rods 14, are positioned just outside of the recesses 9 formed in the side walls 4, thereby permitting vertical movement of the pivot rods 14 in the event of the buckling of a pair of grate and hinge plates. The height of the recesses 9 is such that vertical movement of the rollers 13 and, as a consequence, the pivot rods 15, is prevented. Hence, it can be seen that each pair of plates is so mounted as to permit a buckling or upward movement of the same upon the application of force to one end thereof.

One method of applying force to the several pairs 18 of plates to cause the above-noted buckling, is shown in Fig. 1, wherein a rack 23 is mounted on the edge of the hopper plate 16 nearest the side wall 4. The rack 23 meshes with a pinion 24 mounted on a shaft 25 which extends across the furnace opening 6. The shaft may be actuated by means of an operating handle 26. A second rack and pinion are mounted on the opposite side of the furnace opening 6 for cooperation with the main shaft 25.

In order to facilitate the successive buckling of the several pairs of grate and hinge plates in each of the longitudinal series I provide a pair of tripping rods 30 (Figs. 2, 4 and 5), which are positioned on opposite sides of the grate structure 5 and which extend longitudinally of the same from a point just beyond the outer end of the hopper plate 16 to a point adjacent to the anchor plate 17. The inner ends of the tripping rods 30 are provided with longitudinally extending slots 31 adapted to receive supporting pins 32 carried by the side rails 7. The outer ends of the tripping rods 30 terminate in pivoted handle portions 33 which are provided with notches 34 adapted to successively engage retaining pins 35 carried by lugs 36 extending downwardly from the hopper plates 16, whereby the tripping rods 30 may be retained in either their normal or forward position, as shown in Figs. 1 and 2, respectively. The retaining pins 35 may be held in resilient engagement with desired notches 34 by means of springs 37 which extend from the underside of the

hopper plate 16 into engagement with the handle portions 33.

Each of the tripping rods 30 is provided with a series of spaced cams or raised portions 38 which are adapted to successively engage adjacent hub portions 39 formed on the undersides of the inner ends of the grate plates 19. The spacing of the first cam 38 is such that as the handle portion 33, and consequently the trip rod 30, is moved from the normal position shown in Fig. 1 to the rearward position shown in Fig. 2, the first cam 38 of the series engages the hub portion 39 of the first pair of plates causing the same to buckle slightly. If the operating handle 26 is now moved so as to actuate the hopper plate 16 rearwardly, the buckling of the other pairs 18 of plates in each of the longitudinal series continues to a degree depending upon the force applied.

The degree of buckling of each pair of plates 18 in each of the longitudinal series may be determined by spacing bars or rods 40, there being one pair of bars 40 for each transverse series of pairs of grate and hinge plates. As shown in Fig. 5, for example, the ends of that pivot rod 15 which supports the hopper plate 16 also supports the outer ends of one pair of bars 40. The inner ends of this pair of bars are provided with slots 41 so as to engage slidably the corresponding ends of the next adjacent pivot bar 15, the length of the slots 41 determining, in each instance, the minimum angle between the grate and hinge plates as well as the movement of the hopper-plate pivot rod 15 and the adjacent pivot rod 14. The buckling of successive pairs of plates is similarly controlled by additional pairs of bars 40 as shown in Figs. 1, 2 and 5, opposite ends of which are in pivotal engagement with one pivot rod 15 and in slotted engagement with the next succeeding pivot rod 15.

The spacing of the next succeeding cam 38 is such that as the first pair of plates (Fig. 1) completes its buckling operation, the continued movement of the handle 26 causes the next succeeding pair of plates to be tripped and buckled, and this action continues until all the pairs of plates have been buckled, as shown in Fig. 2.

A fuel hopper or chute 42 extends into the furnace opening 6 to a point just above the grate structure 5. The ashes and clinkers, which are moved over the anchor plate 17 and under the feeding action of the grate structure 5, pass onto a dumping plate 43 positioned between the anchor plate 17 and the rear wall 2. The dumping plate 43 may be controlled by any well known means and, when released, causes the ashes to discharge into an ash pit 44 positioned directly beneath the same.

When the parts are in the relative positions shown in Fig. 1 of the drawing, the several

grate plates 19 and 20 are in their normal flat position permitting coal to pass from the hopper 42 down onto the upper surface of the grate structure 5. As above pointed out, if the handles 33 are moved from the normal position shown in Fig. 1 to the rearward position shown in Fig. 2, the first cam 38 on each tripper rod 30 is moved into engagement with the hub portions 39 of the first pair of plates, causing the same to buckle slightly. If the operating handle 26 is now turned in a counter-clockwise direction, the hopper plate 16 tends to move rearwardly, causing the buckling action to continue until the pivot rod 15 engages the outer end of the first pair of slots 41 in the spacing rods 40, at which point the raised or buckled plates are substantially at right angles.

As the first pair of plates completes its buckling operation, the next succeeding cam 38 on each tripper rod 30 is moved into engagement with the hub portion 39 of the next succeeding pair of plates, so that the further actuation of the operating handle 26 causes these plates to buckle as in the case of the first pair of plates, and this action continues until all the pairs of plates have been buckled, forming the raised grate structure of Fig. 2.

As the plates are successively buckled, the fuel bed is carried rearwardly without any packing due to one portion of the fuel bed pushing against a succeeding portion. The buckling movement of the pairs of grate and hinge plates also opens up the fuel bed, which tends to prevent clinker formation and which further facilitates the free passage of air through the fuel bed.

When the direction of movement of the operating arm 26 is reversed, the pairs of grate and hinge plates are successively returned to their original flat position. The return movement of the plates has a tendency to slide the entire fuel bed toward the front wall 1, but this is avoided by the retarding action of the coal carried rearwardly from the hopper 42 on the rearward movement of the grate structure 5. If anything, the tendency for a forward movement of the fuel bed, as the grate structure 5 is returned to its normal position, is something of an advantage in that it causes the closing up of such voids in the fuel bed as may have been formed during the rearward movement of the grate structure 5.

My invention further contemplates a grate structure which is so designed that any desired transverse series of pairs 18 of grate and hinge plates may be raised or lowered and moved forward or backward without materially affecting the structure of the fuel bed adjacent to that particular transverse section. To this end, I provide additional notches 44 in the tripping rods 30, which are so spaced as to permit the locking

of the rods 30 in a position wherein the desired cam 36 engages the desired hub portion 39. The subsequent rocking of the operating lever 26, causes a movement of the desired transverse series of pairs of grate and hinge plates.

While I have shown only one embodiment of my invention, for the purpose of describing the same and illustrating its principles of construction and of operation, it is apparent that various changes and modifications may be made thereon, without departing from the spirit of my invention. I desire, therefore, that only such limitations shall be imposed thereon as are indicated in the appended claims, or as are demanded by the prior art.

I claim:

1. A grate structure comprising a longitudinal series of pivotally connected grate and hinge plates, said grate plates alternating with said hinge plates, and tripping means operable to cause the buckling of pairs of said grate and hinge plates upon an application of force to one end of said grate structure.

2. A grate structure comprising a plurality of connected grate and hinge plates, said grate plates alternating with said hinge plates, means for exerting a longitudinal force on said plurality of plates and an additional force on certain of said plates, and means for so supporting said plates that said forces may cause the buckling of successive pairs of grate and hinge plates and the bodily movement of one portion of said grate structure upon said buckling.

3. A movable grate structure comprising a longitudinal series of pairs of plates, a plurality of pivot rods for operatively connecting said pairs of plates, pivot rods individual to each pair of plates, means for preventing a vertical movement of the pivot rods of one group, tripping means for causing the initial buckling of at least one of said pairs of plates, and means for exerting a force on the grate structure, whereby said pairs of plates may be buckled to a predetermined extent.

4. A grate structure comprising a longitudinal series of pivotally connected plates, and means for creating a progressive advancement of fuel from one end of said grate to the other comprising mechanism for longitudinally reciprocating one end of said grate, means for anchoring the opposite end of the grate and restraining guides for certain of the plate-connecting pivots, the others of said pivots being free to move from the normal plane of the grate to thereby permit a predetermined upward buckling of said plates under the reciprocating action.

5. In a stoker, an inclined grate structure comprising a longitudinal series of pivotally connected plates, and means for progressive-

ly advancing fuel from one end of said grate to the other including means for giving a longitudinal reciprocating action to the upper end of said series, and restraining guides for certain of the plate-connecting pivots, the other pivots being free to move out of the normal plane of said grate to permit a predetermined upward buckling of the pivoted plates under the reciprocating action.

6. A movable grate structure comprising a longitudinal series of pairs of plates, a plurality of pivot rods for operatively connecting said pairs of plates, pivot rods individual to each pair of plates, recessed side walls incorporating restraining guides for said first-mentioned rods, said individual pivot rods being shorter than the first-mentioned rods to thereby avoid said guides and to permit buckling of said pairs of plates, and reciprocating mechanism attached to one end of said series of plates and operative thereon in a direction longitudinally of said series whereby said plates are alternately buckled and retracted to the normal positions.

7. A reciprocally movable grate structure comprising a longitudinal series of pairs of plates, a plurality of pivot rods for operatively connecting said pairs of plates, pivot rods individual to each pair of plates, said first-mentioned rods being of a different length than said second-mentioned rods, a pair of spaced walls provided with grooves forming guides for the longer rods, means extending from said wall providing a track outside of said groove for the shorter rods, and reciprocating mechanism attached to one end of said series of plates and operative thereon in a direction longitudinally of said series whereby said plates are alternately buckled and retracted to the normal positions.

8. In apparatus of the character described, a movable grate structure comprising a longitudinal series of pairs of plates, a plurality of pivot rods for operatively connecting said pairs of plates, pivot rods individual to each pair of plates, said first-mentioned rods being of a different length than said second-mentioned rods, a pair of spaced walls provided with grooves forming guides for the longer rods, and means extending from said wall providing a track outside of said groove for the shorter rods, reciprocating mechanism attached to one end of said series of plates and operative thereon in a direction longitudinally of said series whereby said plates are alternately buckled and retracted to the normal positions.

9. A fuel-feeding structure comprising a longitudinal series of pairs of grate plates and hinge plates, means for pivotally supporting adjacent ends of said successive plates, means for exerting a force on one end of said structure, means coacting with said plates for causing said pairs of grate and

hinge plates to buckle under the action of said force, and means for limiting the extent of the buckling of said pairs of plates.

10. An articulated grate consisting of relatively long and short fuel-supporting elements hinged together in longitudinal series, with a long element preceding each short element from the front end of the grate toward the rear, the hinge joint between each short element and the preceding long element being free to rise from the normal plane of the grate, means restraining the other hinge joints to movement substantially in the said normal plane, means for exerting longitudinal pressure on the grate at the forward end, and means for guiding the said free joints upwardly to effect buckling of the grate at the free hinge joints under action of said pressure.
